United States Patent Office

Des. 193,880
Patented Oct. 16, 1962

193,880

PASSENGER AIRCRAFT

Lawrence B. Rellis, 5123 W. Deming Place, Chicago, Ill.

Filed Nov. 13, 1961, Ser. No. 67,498

Term of patent 3½ years

(Cl. D71—1)

Eq. 1

Eq. 2

E-F-3

Eq. 4

FIG. 1 is a side elevational view of a passenger aircraft embodying my new design, the high lift flaps on the leading edges of the wings being in the up, open position.

FIG. 2 is a front elevational view thereof.

FIG. 3 is a top plan view thereof.

FIG. 4 is a bottom plan view thereof in flight condition; and

FIG. 5 is a rear elevational view thereof.

The side opposite that shown in FIG. 1 is a mirror image thereof.

I claim:

The ornamental design for a passenger aircraft, as shown and described.
